MOUNTING FOR TUNING ELEMENTS

Jerome C. Smith, Merchantville, N. J., assignor to
 Radio Corporation of America, a corporation of
 Delaware

Application August 31, 1935, Serial No. 38,838

15 Claims. (Cl. 250—16)

This invention relates to radio apparatus, particularly to tuning elements and has special reference to improvements in non-microphonic mountings for devices of this general type. While 5 the invention will be described in connection with capacity type tuning elements it is to be understood that the invention is not limited to such application as the disclosure in this respect is merely illustrative for purposes of explaining 10 the inventive concept.

The specification and claims defining the invention will be best understood by reference to the accompanying drawing wherein:

Fig. 1 is an end elevation partly in section of a 15 tuning element mounted in accordance with the prior art; it is included for the purpose of illustrating the problem involved.

Fig. 2 is an end elevation partly in section of a tuning element assembly mounted in accordance 20 with the present invention.

Fig. 3 is a top plan view of the invention as embodied in Fig. 2 showing the assembly suspended or "cradled" at three points,

Fig. 4 is a fragmentary top plan view of a modified form of the invention,

Fig. 5 is a fragmentary elevation showing a modified form of vibration-insulating member,

Fig. 6 is a front elevation partly in section of another embodiment of the invention.

30 Radio installations, especially modern high frequency receivers, are extremely sensitive in their performance to mechanical shocks and jars. Such disturbances tend to set up microphonic and/or other parasitic tremors which when amplified and translated by the various electric instruments in the set are acoustically or visually noticeable, as the case may be, in the output device.

In an effort to obviate these spurious vibrations 40 early experimenters provided chassis, panels and bases resiliently mounted, as on springs or on rubber or felt. Such expedients, however, were found less satisfactory than desirable since, while partially effective in insulating the set from external forces, they have but little damping effect 45 upon vibrations arising or appearing in the apparatus itself. As recorded by Taylor and White (U. S. P. 1,669,217, filed October 17, 1925, page 1, lines 65-70) it was observed that distortion increased with the frequency to which the apparatus was tuned and a large part of the trouble was traced to vibration of the condenser plates. Taylor and White found that microphonic noises in the receiving circuits were substantially reduced by providing, in addition to the usual re-

silient set-mountings, a tuning arrangement including condenser plates made of low resistance material having a natural period of vibration below or above the audible range.

Roberts and Van Dyck working independently, 5 about that time, provided a less complicated vibration damping arrangement by mounting the tuning condenser assembly upon individual resilient supports. This manner of isolating the several elements of the set from extraneous vibrations has since received wide favor but, as will be apparent upon a careful analysis of the vibration-producing stresses, falls far short of providing perfect freedom from distortion.

Thus, referring to Fig. 1, which is an end view 15 of a tuning element mounted in accordance with the prior art and is included for purposes of illustrating the problem involved. This figure shows a condenser plate 1 disposed for rotation upon a rotor shaft 2. The shaft is carried, 20 usually off center, by an end plate 3 and the entire assembly supported by rubber grommets 4 and 5. The grommets are fixed to the chassis or base 6 of the set as by screws 7 which extend through washers 4' 5' on the underside of the 25 base 6.

It will be observed in connection with this typical prior art installation that if there is a tendency for the assembly to move up and down, as at A (due to chassis vibration as caused by a 30 loudspeaker, not shown) the weight of the assembly is concentrated over one or the other of the supports, permitting one corner to rise and fall in step with the disturbance, thus twisting one end plate with respect to the other and 35 causing a shift in the condenser plate placement.

Similarly if there is a tendency to make this unit shift lengthwise (i. e. perpendicular to the plane of the paper) near the top as at B, the rotor 1 together with the upper part of the frame 40 may start vibrating slightly, which will cause a change in capacity in the lower section C since the stator plates are there relatively stationary. Further, since the shaft 2 is off center, cross-wise vibration, as shown by arrow D, has a lever-age on the supporting rubber grommets 4-5 which will concentrate the movement adjacent the top of the assembly.

Another and very real disadvantage of prior 50 art mountings especially apparent in modern receivers—where the drive mechanism is rigidly fixed on the chassis and the condenser is flexibly mounted—is indicated by the arrows E—E showing the rocking motion which will usually accompany movement of the tuning knob. This 55

rocking movement produces an effect which is very similar to back-lash and makes accurate tuning difficult.

A principal object of the present invention is to provide a supporting arrangement for tuning elements and the like obviating the above and other disadvantages inherent in prior art mountings.

Another object of the invention is to provide a mounting arrangement for tuning elements wherein the axis of support lies in a plane adjacent the center of gravity of the elements supported.

Another object is to provide a mounting for tuning elements wherein the elements to be supported are effectively cradled against vibration-producing stresses and strains.

Referring now to Figs. 2 and 3 which show a preferred embodiment of the invention as applied to an assembly of tuning elements of the capacity type. The assembly itself is provided with a front end plate 21 and a rear end plate 23, each journaled to accommodate a shaft 25 upon which the rotor plates 27 are mounted. Rods 31 and 33 support the stator plates 29 and rods 35 and 37 carry a number of shielding plates 39 and lend rigidity to the assembly.

In accordance with the principle of the invention the assembly is suspended, as from a bridge, at points in a plane substantially adjacent its center of gravity. The center of gravity will usually lie in a plane adjacent the mid-section of the tuning assembly, its exact position depending, of course, upon the particular type and construction of the assembly. The supporting structure employed in carrying the invention into effect may comprise an L beam 41 extending across and preferably projecting beyond the opposite side edges of the front face plate 21. Plate 21 lies in face to face relation with the perpendicular arm 41a of L beam 41 and is fixed thereto as by means of rivets 43-45 arranged in spaced relation on opposite sides of the rotor shaft 25. The projecting portions of the horizontal arm 41b of beam 41 rest upon grommets 47-49 of rubber or other vibration insulating material carried respectively by risers or studs 51-53 and are secured thereto as by means of nuts 51' and 53' threaded on the end section of the studs. The studs are secured to the base 54 on its underside as by means of rivets 55 and 57.

The studs 51-53 are preferably spaced apart a distance greater than that required to accommodate the tuning assembly. As shown in Figs. 2 and 3 the number of supporting points, and hence the number of studs may be limited, in the interests of economy, to the minimum number required to define the plane in which the assembly is supported, i. e. three. In these figures the third grommet is designated 59 and the stud 61. The rear end plate 23 is provided with an L flange member 63, one arm of which is fixed to its outer surface and the other is secured to its grommet 53, in a manner similar to that described 63 in connection with the front plate 21.

If desired the tuning assembly may be suspended between two pairs of supporting studs, in which case, as indicated in Fig. 4 the rear mounting arrangement including the beam 141 spanning the resilient grommets 147-149 may be similar in all respects to that previously described.

It is not always necessary to mount the bridging L beams directly upon the resilient members, they may, as shown in Fig. 5, be connected directly to the metal studs 253 and the studs in-

sulated from extraneous vibrations by grommets 249 adjacent the base 54.

Fig. 6 shows another embodiment of the invention wherein the tuning element assembly 21 is suspended from its mid-section on an L beam 541 which bridges an orifice 354a in the base 354. The bridging member rests upon rubber grommets 347-349 which are fixed directly to the base by short studs 351-353. The studs are insulated from the underside of the base by washers 10 351'-353'. As in the other embodiments the assembly is suspended in a plane, substantially adjacent its center of gravity. Here, however, the "well" formed by the orifice 254a accommodates the lower part of the unit and the plane 15 in which it is supported coincides substantially with the plane of the base 354.

The improved operating performance of condensers mounted in accordance with the present invention may be attributed in part to the fact 20 that any vibrations which may be transmitted through the supports tend to move the rotor and stator plates together so that they are not displaced with respect to each other and consequently produce little or no change in 25 capacitance. Further, since the rubber "feet" provide a relatively wider base than hitherto employed, torsional stability is augmented and back-lash substantially obviated.

In carrying the invention into effect various 30 changes may be made in the above described embodiments of the invention without departing from the spirit and scope of the appended claims.

What is claimed is:

1. In combination in radio apparatus, a variable tuning element, a chassis having a base, means independent of supporting structure for said chassis for supporting said tuning element on said chassis base, said means being attached to said variable tuning element adjacent the level 49 of the center of gravity thereof and comprising vibration damping means interposed between said tuning element and base.

2. The invention as set forth in claim 1 where- 45 in the means for supporting said tuning element includes a plurality of vibration damping elements disposed adjacent the level of the center of gravity of said tuning element.

3. The invention as set forth in claim 1 where- 50 in the plane in which said tuning element is sup- ported coincides substantially with the plane of said chassis base.

4. In combination in radio apparatus, a variable tuning element, a chassis having a base, and means including a resilient member intermediate 55 said base tuning element for supporting said tuning element adjacent the level of the center of gravity thereof, said means constituting the sole support for said tuning element and being independent of supporting structure for said chassis. 60

5. In combination in radio apparatus, a varia- 65 ble tuning element constituted by a pair of end plates having a plurality of interposed condenser elements and a shaft for said elements journaled centrally in said plates and projecting therefrom, a chassis having a base, means independent of supporting structure for said chassis for supporting said tuning element on said chassis base, said means comprising a plurality of spaced studs on said base, support members fixed to said end plates and to said studs adjacent the level containing the center of gravity of said tuning element, and vibration damping elements fixed to said studs intermediate said support members and said base, said studs being spaced apart a distance 75

substantially greater than that required to accommodate said tuning element and being substantially equally spaced from said tuning shaft and from the points whereat said support members are affixed to said end plates.

5. In combination in radio apparatus, a variable tuning element, a chassis having a base, means independent of supporting structure for said chassis for supporting said tuning element on said chassis base, said means comprising a plurality of spaced studs on said base, support members fixed to said tuning element and to said studs adjacent the level containing the center of gravity of said tuning element and vibration damping elements fixed to said studs intermediate said support members and said base.

10. The combination set forth in claim 6 wherein in said studs are spaced apart a distance substantially greater than that required to accommodate said tuning element.

15. The combination set forth in claim 6 wherein the number of studs corresponds to the minimum number of points required to define the plane of support for said tuning element.

20. The combination set forth in claim 6 wherein in four studs are provided, the studs of each pair having support members common thereto.

25. The combination set forth in claim 6 wherein the center of gravity of said tuning ele-

ment falls on a line parallel to a line drawn through a point substantially midway between two of said studs and perpendicular to said base.

11. The combination set forth in claim 6 wherein said support members are affixed to said tuning element at points substantially equally distant from a point midway between two of said studs.

12. The combination set forth in claim 6 wherein said tuning element is suspended adjacent points substantially midway between the top and bottom thereof.

13. The combination set forth in claim 6 wherein said vibration damping elements are interposed between said studs and support members.

14. The combination set forth in claim 6 wherein vibration damping means are interposed between said base and said studs.

15. A variable tuning device comprising rotor and stator elements, means including an end plate for maintaining said elements in alignment, and means comprising a pair of outwardly extending oppositely located arms for mounting said device, the outer extremities of said arms being spaced apart a distance substantially greater than is necessary to accommodate said device.
